WILLIAM ERNEST CLIFTON AND JOHN STURTON EWART, OF NOTTINGHAM, ENGLAND,
ASSIGNORS TO THE CLIFTOPHONE LIMITED, OF LONDON, ENGLAND.

SOUND RECORDING AND REPRODUCING INSTRUMENT.

Application filed June 21, 1921. Serial No. 479,379.

To all whom it may concern:

Be it known that we, WILLIAM ERNEST CLIFTON and JOHN STURTON EWART, subjects of the King of England, both residing 5 in Nottingham, England, have invented certain new and useful Improvements in Sound Recording and Reproducing Instruments, of which the following is a specification.

This invention consists in improvements 10 in or relating to sound-recording and reproducing instruments for use with gramophones and like machines of the flat disc-record type in which the stylus bar is pivoted intermediate of its two ends in the 15 sound box casing and is directly connected at its inner end to the diaphragm or a part rigidly connected therewith without the interposition of a link, and refers particularly to the construction of a diaphragm or 20 vibratory membrane therefor. The principal object of the invention is to provide a diaphragm by which a purer tone and a better balance between treble and bass registers will be obtained than has been possible 25 heretofore, and to enable the diaphragm, where it is connected to the stylus bar, to move readily through substantially the same arc as that through which the end of the stylus bar moves.

30 In instruments of this type hitherto, hereinafter referred to for brevity by the term "sound-box" the diaphragm has generally been constituted by a comparatively stiff and elastic disc of material rigidly held 35 around its margin in the casing of the sound-box. To the centre of the diaphragm is firmly connected one end of a stylus-bar or lever pivotally mounted intermediate of its length in the sound-box casing so that 40 it can oscillate in a plane at right-angles to that of the diaphragm. The other end of the lever is fitted with a needle the point of which serves either to record on a plastic body vibrations imparted to the diaphragm 45 or, in reproducing, to be oscillated by the record to transmit vibrations to the diaphragm. In such a construction the stylus-bar, which oscillates about a fixed axis, endeavors to move that point of the diaphragm to which it is attached in an arc 50 struck from the axis of pivoting but a diaphragm of the nature referred to is not adapted to follow this movement. Moreover, the diaphragm is not adapted to

be moved to any appreciable extent without stretching or distorting the material of the diaphragm unless the edge of the latter is free to move in its connection with the sound-box.

Diaphragms have been suggested wherein 55 the central portion has been composed of relatively stiff material and the portion surrounding it has been of more flexible material. In such a case the stiffened central portion was secured at its centre to the end 60 of the stylus-bar and this again was not found to produce the satisfactory results obtained with the improved diaphragm of 65 this invention.

According to the present invention a diaphragm is composed of flexible and substantially non-resilient or only slightly resilient material and has a relatively stiff portion which is disposed in the middle or 70 partly in the middle of the diaphragm and is formed for connection with the inner end 75 of the stylus-bar at a position which is eccentric in the said relatively stiff portion. Thus the latter may conveniently be constituted by a radial strip having straight, parallel or tapered sides or of lozenge or oval shape, the strip being formed for connection with the inner end of the stylus-bar at or near an edge which is adjacent to the 80 centre of the diaphragm.

The term "non-resilient," as applied to the main portion of the diaphragm, is to be understood to mean that the portion thus denoted is non-resilient as compared with diaphragms in general use, such as mica or 85 metal diaphragms. Thus the relatively stiff portion is included in a readily flexible disc of material which is mainly non-resilient by comparison with the relatively stiff portion or with diaphragms in general use 90 and results in a diaphragm which is totally 95 different in effect to one in which a stiffener is applied to material having the usual degree of resilience such as is possessed by mica or metal sheet for example. A diaphragm according to the present invention leaves the relatively stiff radial strip free 100 to vibrate readily with but little restraint imposed upon it from the surrounding portion by reason of the comparative non-resilience and flexibility of the latter.

Preferably the relatively stiff portion or strip is rendered more rigid in the region

of its edge at which it is connected to the stylus-bar than is the remainder of it.

According to a feature of the invention, movement of the relatively stiff portion is controlled in such a manner that a part of it in the region of its connection with the stylus-bar will travel along substantially the same arc as that over which the inner end of the stylus-bar will move. In order so to control movement of the strip, in one form of the invention, it is combined with a second relatively stiff and substantially radial strip which extends inwardly from the opposite end of a diameter of the diaphragm from that from which the first strip extends, the said second strip being operatively connected to the first strip and of such a character as to constrain the aforesaid portion of the first strip which is connected to the stylus-bar to move in the desired arc. If the meeting-edges of the two strips are overlapped this overlapping will afford the increased rigidity at the edge of the strip referred to above.

The invention also includes the particular manner in which the diaphragm is built up and this and other features of the invention will be more clearly understood from the following detailed description, given by way of example only, with the aid of the accompanying drawings in which—

Figures 1, 2 and 3 illustrate component parts of a built-up diaphragm according to one form of the invention;

Figure 4 is a view showing the complete diaphragm mounted in a sound-box;

Figures 5, 6 and 7 show respectively modified forms of diaphragm according to the invention;

Figure 8 illustrates the diaphragm having two radial strips;

Figure 9 is a section on an enlarged scale on the line 9—9 of Figure 8;

Figure 10 is a view of a still further construction of diaphragm;

Figure 11 is a section on the line 11—11 of Figure 10; and

Figure 12 is a section on the line 12—12 of Figure 10.

Like reference numerals indicate like parts in the several figures of the drawings.

In the form shown in Figures 1—4, a diaphragm is constructed of a portion 20 of flexible and substantially inelastic material such, for example, as oiled silk, having a part cut away as at 21 within which is fitted a strip 22 (Figure 1) of stiffer material, such for example as mica. The parts 20 and 22 are disposed between two outer covering discs such as 23 (Figure 3) of thin flexible material, preferably paper, the parts being secured together by suitable adhesive. By removing the portion 21 from the part 20 the diaphragm is of substantially uniform thickness over its whole area. The

composite diaphragm is shown in Figure 4 as assembled in a sound-box casing of known construction with the inner end of the stylus-bar 25 firmly secured at 26 to the diaphragm at a position near the inner edge of the strip 22; that is to say at a position in the strip which is eccentric therein.

The part 22, which is of relatively stiff material, can, by reason of the flexibility of the material surrounding it, move bodily and, where it is connected to the stylus-bar, in substantially the same arc as that over which the end of the stylus-bar will move. The more flexible portion of the diaphragm surrounding the part 22 permits comparatively free movement of the latter and the diaphragm therefore does not cramp the movement of the stylus-bar.

The oiled silk part 20 prevents the paper or like discs 23 from becoming too stiff as might be the case were they cemented directly together. The oiled silk 20 is found not only to maintain the flexibility of the diaphragm but to serve also to eliminate crackling or other extraneous noise arising from the diaphragm itself.

If preferred, the oiled silk may be replaced by a thin film of celluloid having a stiffened portion similar to 22 but generally speaking when celluloid or like material is employed the diaphragm will be built up in the manner to be described with reference to Figures 10—12.

It is not necessary that the relatively stiff portion or blade 22 should extend to and beneath the edge of the sound-box-casing as shown in Figure 4. The part 22 may have the form shown in Figure 6 or Figure 7 but in either case it will be connected to the inner end of the stylus-bar at a position indicated at 26 which is eccentric in the part 22.

The forms of diaphragm shown in Figures 6 and 7 may be built up in the manner described with reference to Figures 1—4, or the parts 22 for example of paper, may be cemented to the surface of, for example, a thin celluloid disc thus affording a relatively stiff portion or blade in continuity with the remainder of the disc. The celluloid or like disc is indicated at 27 and takes the place of the parts 20 and 23 of Figures 1—4. It will be seen that the stylus bar 25, which is connected to the sound box casing so as to oscillate approximately about an axis indicated by the line 50, is connected eccentrically to the part 22 so as to overlie the latter along the greater portion of its length. This has much the same effect as will be obtained with the construction illustrated in the other figures of the drawings, in which the stylus bar is connected to the inner end of a radial relatively stiff strip so as to overlie the greater portion of the length thereof. One purpose of so connecting the stylus bar to the relatively stiff portion is so

that the inner end of the stylus bar and that part of the diaphragm to which it is connected shall both be enabled to move over approximately the same arc without material restraint during the oscillation of the stylus bar while sound recording or sound reproducing.

It will be appreciated that the stylus bar will be similarly connected to the diaphragms illustrated in Figures 5 and 6 and 8 to 12, respectively, but, for the sake of clearness, the stylus bar has been omitted from the drawings.

Figure 5 shows a method of constructing a diaphragm having characteristics similar to those above described and in this case a disc of mica or other material 28 is weakened or rendered more flexible by perforations 29 at all parts of it except the central portion 22, which constitutes substantially the equivalent of the relatively stiff portions 22 in the foregoing examples. In this case the disc 28 will be covered on one or on both sides with thin paper as in the first described example, in order to close the perforations.

In Figures 10-12 is illustrated a still further modification of diaphragm construction in which a disc 30, conveniently of thin celluloid, is corrugated with the circular marginal corrugation 31 and cross corrugations 32 and 33 in order to render it as yieldable as possible. The relatively stiff portion is formed by cementing one or more pieces of paper or other suitable material on one or both sides of the diaphragm as shown at 22, and in order to render that edge of the stiffened portion, where the stylus-bar is connected to it, more rigid than the remainder of it, a cross-strip of paper or celluloid or other material 34 is cemented over one of the strips 22. The diaphragm may obviously be corrugated in other manners than that shown in the drawings in order to give it the desired additional flexibility.

In this, and in the other constructions in which celluloid is employed as the flexible portion of the diaphragm and paper is used as the stiffener it is found to be advantageous to utilize a solution of celluloid in amyl-acetate or other celluloid solvent as the adhesive for securing the paper strips to the celluloid of the diaphragm. The paper should be a smooth surfaced paper, particularly that side of it which is to adhere to the celluloid diaphragm.

It is preferred to construct the stiffened portion 22 of the diaphragm of such stiffness that, with rapid vibrations such as are associated with treble notes, vibration is imparted mainly to the region in which the stylus-bar is connected but with the less rapid vibrations, for example, of the bass notes, the whole of the relatively stiff portion may be vibrated and possibly moved

bodily. The flexibility of the portion of the diaphragm surrounding the stiffer portion should be such as to permit these vibrations with as little tendency to resist or interfere with them as possible.

It will be obvious that whereas the stylus-bar oscillates about an axis generally outside the sound-box casing, the stiffer portion 22 will tend to vibrate or oscillate about an axis nearer to the point of connection of the stylus-bar with the diaphragm. Thus, at this point of connection, the inner end of the stylus-bar tends to move along an arc of greater radius than does the equivalent point of the stiffer portion of the diaphragm, with the result that in course of time the connection between the stylus-bar and the diaphragm runs the risk of becoming damaged or loosened. In Figures 8 and 9 a construction is illustrated which tends to mitigate this objection and for this purpose the flexible portion or disc 27, for example of celluloid, has secured, on one face of it, a stiffening portion 22, for example of paper, as in the example shown in Figure 6. On the other face of the disc 27 is a second strip 35, conveniently also of paper, whose inner end overlaps the inner end of the portion 22. The stiffness of the parts 22 and 35 is so chosen that under the influence of the vibration from the stylus-bar the two portions mutually co-act in such a manner as to cause the point 26 of the composite diaphragm to move naturally along the same, or approximately the same, arc as that along which the inner end of the stylus-bar will move. At the same time the overlapping portions of the parts 22 and 35 afford the equivalent of the cross-strip 34 in Figure 12, which not only tends to strengthen the diaphragm in the region of its connection with the stylus-bar, but also tends to prevent buckling of the stiffened portions 22 and 35. The effect of this is to assist the strip to flex about lines at right-angles to the stylus-bar and parallel with the plane of the diaphragm and to tend to limit buckling to a bending only about the centre line indicated, for example, by the section-line 9-9 of Figure 8 and about an axis at right-angles thereto.

In the constructions illustrated in Figures 6 to 11, materials of the following dimensions are found to give good results.

The diameter of the diaphragm disc exposed within the opening of the sound-box is approximately $1\frac{3}{4}$ inches and the celluloid from which the portion 27 or 30 is formed is approximately fifteen thousandths of an inch thick.

The strip 22, of tough paper, is approximately nine thousandths of an inch thick and the thickness of the strip (also of tough paper) 35, Figures 8 and 9, is approximately eight thousandths of an inch.

Each strip such as 22 or 35 will be about three-fourths of an inch to an inch long and about $\frac{1}{8}$ inch wide at its widest part, e. g. where the two strips overlap in Figures 8 and 9.

It is to be understood that the above dimensions are only given as examples and not as limitations. For instance, the thickness of the disc 27 or 30 may quite satisfactorily be any thickness between eight-thousandths and twenty-thousandths of an inch and that of the strips 22 and 35 may also vary more or less from the dimensions given.

15 It will be obvious that the two strips 22 and 35 could both have been applied to the same side of the disc 27 although it is preferred to apply them to opposite sides thereof as shown.

20 Moreover, it will be understood that corrugations may be formed in the disc 27 of the construction illustrated in Figures 7 and 8 as in the construction illustrated in Figures 9 to 11. The latter figures, bearing in mind the modified outline of the applied strips (or their equivalent) and their disposition, will serve to indicate the form of corrugations which will be applicable.

25 What we claim as our invention and desire to secure by Letters Patent is—

30 1. For a sound box of the type described, a diaphragm comprising a sheet of flexible and substantially non-resilient or only slightly resilient material having a relatively stiff portion formed for connection with the inner end of a stylus bar nearer one edge of the said portion than the other edges thereof and adjacent the center of the diaphragm, substantially as described.

35 2. For a sound box of the type described, a diaphragm comprising a sheet of flexible and substantially non-resilient or only slightly resilient material having a relatively stiff portion adapted to have a stylus bar secured thereto, said portion being disposed eccentrically with respect to the point of attachment of the stylus bar, whereby said point of attachment is nearer one margin of said portion than the other margins thereof, substantially as described.

40 3. For a sound box of the type described, a diaphragm comprising, in combination, a sheet of flexible and substantially non-resilient or only slightly resilient material having a relatively stiff portion constituting a substantially radial strip which extends approximately from the margin of the sound box casing to the center of the diaphragm and is formed for connection with the inner end of a stylus bar at or near an edge of the said strip which is adjacent to the center of the diaphragm, and means to render said relatively stiff portion more rigid in the region where it is connected to the stylus bar than is the remainder of it.

45 4. For a sound box of the type described, a diaphragm comprising a sheet of flexible and substantially non-resilient or only slightly resilient material having a relatively stiff portion constituting a substantially radial strip which extends approximately from the margin of the diaphragm to the center of the diaphragm and is formed for connection with the inner end of a stylus bar at or near an edge of the said strip which is adjacent to the center of the diaphragm, substantially as described.

50 5. For a sound box of the type described, a diaphragm comprising a sheet of flexible and substantially non-resilient or only slightly resilient material having a relatively stiff portion constituting a substantially radial strip extending from approximately the margin of the diaphragm to the center thereof and being formed for connection with the inner end of the stylus bar at or near an edge of the said strip which is adjacent the center of the diaphragm, and a second relatively stiff and substantially radial strip which is operatively engaged to the said first strip and forms therewith a relatively stiff portion eccentrically positioned with respect to the center of the diaphragm, substantially as described.

55 6. For a sound box of the type described, a diaphragm comprising a sheet of flexible and substantially non-resilient or only slightly resilient material having a relatively stiff portion constituting a substantially radial strip which extends approximately from the margin of the diaphragm to the center thereof and is formed for connection with the inner end of a stylus bar at or near an edge of said strip which is adjacent to the center of the diaphragm, and a second radial stiffening strip applied to the diaphragm and extending inwardly from the margin thereof, said second strip overlapping at least a part of said first portion, substantially as described.

60 7. For a sound box of the type described, a composite diaphragm comprising, in combination, a disc of flexible and substantially non-resilient material, and a radial stiffening blade incorporated therewith and comprising a radially disposed member extending approximately from the margin of the sound box casing and the center of the disc, and means to secure the disc and the strip together.

65 8. For a sound box of the type described, a diaphragm composed of flexible and substantially non-resilient material formed with a relatively stiff portion eccentrically disposed therein and formed for connection with a stylus bar without the interposition of a swinging link in such manner that the stylus bar will overlie the major length of the relatively stiff portion, substantially as described.

9. For a sound box of the type described, a diaphragm comprising a sheet of flexible, substantially non-resilient material formed with a relatively stiff portion constituting a 5 radial strip extending approximately from one margin of the diaphragm to the center thereof and formed for connection with a stylus bar without the interposition of a swinging link, the connection between the 10 stylus bar and the relatively stiff portion being at or near an edge of the latter which is adjacent to the center of the diaphragm, substantially as described.
10. For a sound box of the type described, 15 a diaphragm comprising a sheet of flexible and substantially non-resilient material having a relatively stiff portion constituting a substantially radial strip extending approximately from the margin of the dia- 20 phragm to the center thereof and formed to connect with a stylus bar at or near an edge of said strip which is adjacent to the center of the diaphragm, and a second ra- 25 dial stiffening strip applied to the dia- phragm and overlapping at least a portion
- of the first mentioned strip, substantially as described.
11. For a sound box of the type described, a diaphragm comprising a sheet of flexible and substantially non-resilient material 30 having a relatively stiff portion constituting a substantially radial strip which extends approximately from the margin of the dia- phragm to the center thereof and formed to connect with a stylus bar at or near an 35 edge of said strip which is adjacent to the center of the diaphragm, and a second ra- 40 dial stiffening strip applied to the dia- phragm and forming with said first portion a relatively stiff portion eccentrically posi- tioned with respect to the center of the dia- phragm, substantially as described.

In testimony whereof we have signed our names to this specification in the presence of two subscribing witnesses.
